UNITED STATES PATENT OFFICE

157,435

CANDY CONTAINER OR THE LIKE

J. W. Rucker, Fort Worth, Tex., assignor to Loma Plastics, Inc., Fort Worth, Tex., a corporation of Texas

Application November 1, 1948, Serial No. 149,429

Term of patent 14 years

(Cl. D58—11)

To all whom it may concern:

Be it known that I, J. W. Rucker, a citizen of the United States, residing at Fort Worth, in the county of Tarrant and State of Texas, have invented a new, original, and ornamental Design for Candy Container or the like, of which the following is a specification, reference being had to the accompanying drawing, forming part thereof.

I claim:

The ornamental design for a candy container or the like, substantially as shown.

J. W. RUCKER.
